UNITED STATES PATENT OFFICE.

CARL A. S. SWANSON, OF MALDEN, MASSACHUSETTS, ASSIGNOR TO CARL A. S. SWANSON, TRUSTEE, OF MALDEN, MASSACHUSETTS.

METHOD OF CONSERVING HEADER PLUGS.

Application filed September 23, 1925. Serial No. 58,065.

This invention aims to provide improvements in oil stills, and more particularly to an improved method of conserving header plugs.

5 In the drawings which illustrate a preferred embodiment of my invention:—

Fig. 1 is an end elevation of a portion of a still showing some of the headers connecting the pipes;

10 Fig. 2 is a section through a portion of the still showing the general layout of the oil conducting pipes;

Fig. 3 is an end elevation of one of the headers;

15 Fig. 4 is a section of the header taken on the line 4—4 of Fig. 3; and

Fig. 5 is an elevation of a preferred form of plug for use in closing the cleanouts provided in each header.

20 After each run of an oil still it is ordinarily necessary to clean all the tubes with a tube cleaner. In practice the workmen cleaning the stills usually ruin the threads in the headers at the cleanout openings 3 during introduction, use and removal of the tube cleaner. Therefore it is ordinarily necessary to retap the cleanouts after each cleaning of the tubes of the oil still. In so doing, the holes are made larger and

25 therefore a larger plug is required. Heretofore the practice has been to carry on hand a large number of plugs of various sizes and each time the openings 3 were retapped new and larger plugs were inserted, requiring the

30 keeping in stock of a very large number of plugs and the careful selection of the correct plug each time a change was made.

Referring to the drawings, the stills as illustrated in Figs. 1 and 2 are made up of 40 a series of pipes or tubes 1 generally connected in pairs at their ends by headers 2 which take the place of return bends. The tubes 1 are expanded in the headers as best illustrated in Fig. 4.

45 Each header 2 is provided with a threaded opening or cleanout 3 which is sufficiently large in diameter to permit the tube 1 to pass therethrough and into each opening is threaded a plug 4. Each plug 4 is provided

50 with a relatively long tapered shank portion 5 hollowed out throughout a substantial portion of its length and a tool-engaging portion 6 to receive a tool portion herein shown as a nut 6 for turning the plug into the

55 threaded opening 3. The shank 5 of the

plug may be initially threaded throughout its entire length, as illustrated in Fig. 5, or it may be initially threaded only at its smaller end, the thread being cut further up each time that the plug is to be used in an 60 enlarged opening.

In the type of plug illustrated in the drawings only one is needed for each cleanout 3 thereby doing away with the necessity for carrying on hand a large supply of assorted 65 plugs.

The first time the plug 4 is used in the opening 3 it occupies the position shown at the left of Fig. 4 while at the right of the same figure I have illustrated the position 70 and form of a plug after the opening 3 has been retapped several times. After an opening has been retapped the plug may be screwed into the opening and as a portion of the plug will project into the passage 7 75 in the header after each retapping operation it is desirable to remove the projecting portion so as to prevent reducing the size of the passage through which the oil passes from one pipe to another. This operation 80 is accomplished by reaching through the other opening 3 in the header 2 and scrib- ing the plug 4 which is thereafter removed and the projecting portion sawed off.

The plug 4 is hollowed out, as indicated 85 in Fig. 4, to catch coke, carbon, or other solids, to save metal and to facilitate the sawing off of the plugs after they have been scribed.

While I have shown and described a pre- 90 ferred embodiment of my invention it will be understood that I have done so for purposes of clarification rather than limitation, the invention being best defined in the following claims:

Claims:

1. In the operation of tubular oil stills and the like having elongated tapered header plugs which are required to be removed at more or less frequent intervals, for cleaning 100 purposes, the method which consists in retapping and thereby enlarging damaged threaded openings for the plugs, cutting off the small ends of such plugs as would project too far into the headers and interfere with free circulation after retapping the openings, reinserting the plugs in the openings and repeating the operations until the plugs are too short for further use.

2. In the operation of tubular oil stills 110

and the like having elongated, tapered header plugs which are required to be removed, at more or less frequent intervals, for cleaning purposes, the method which ¹⁰
5 consists in retapping and thereby enlarging damaged threaded openings for the plugs, inserting the plugs in the retapped openings to determine how far their ends project into the header, removing the plugs and cutting off the tapered ends which otherwise would interfere with free circulation in the headers, reinserting the cut-off plugs and repeating the operations as required until the plugs are too short for further use. ¹⁵

In testimony whereof, I have signed my name to this specification.

CARL A. S. SWANSON.
